UNITED STATES PATENT OFFICE

MAURICE D. BRODY, OF CHICAGO, ILLINOIS, ASSIGNOR TO KALMAN STEEL COMPANY, INC., OF CHICAGO, ILLINOIS, A CORPORATION OF DELAWARE

PRODUCTION OF EXPANDED LOAD-BEARING MEMBERS

Application filed April 12, 1927. Serial No. 183,224.

This invention relates to the production of expanded load bearing members and its object is to provide a simple, rapid and economical method, yielding a product of superior 5 quality expanded from a rolled blank and in which the strands are stretched and, together with the associated bonds, lie flat in a common plane. The present method may be practiced with equipment of extremely simple 10 character and which occupies a comparatively small degree of floor space.

Apparatus for practicing the method is illustrated in the accompanying drawings in which:

15 Figure 1 is a plan view of the apparatus, the upper member of the expansion guide being removed.

Figure 2 is a central longitudinal sectional view.

20 Figure 3 is a partial elevation of the rolls by which the blank is slit, the blank being shown at the center of the roll pass.

Figure 4 is a cross section of the expansion guide, showing the blank partly expanded.

25 Figure 5 is a partial elevation of the finishing rolls, the blank being shown at the center of the roll pass.

Figure 6 is a longitudinal sectional view of the expansion guide.

30 Figure 7 is a plan view of the lower member of the expansion guide.

Figures 8, 9 and 10 are cross sections on the lines 8—8, 9—9 and 10—10 of Figure 6.

The blank is rolled in the usual manner to a 35 suitable I-cross section whereby a web W and flanges F are provided and the process is practiced with the blank at a working heat of about 1600° F. The blank may be passed directly from the mill by which it is rolled

40 to the apparatus by which it is expanded in which case no reheating is ordinarily necessary; or if it has been allowed to cool before its delivery to the apparatus for its expansion it may be related in a furnace A from which 45 it is passed to the expansion apparatus. As herein shown the blank is passed through the furnace A in the direction of its length.

The web of the blank is first formed with longitudinal slits arranged in the manner 50 suitable for diamond mesh expansion. These

slits, however, are not formed by the ordinary shearing cutters but by upper and lower rolls 20 and 21 provided with peripheral rows of coincidentally arranged scoring ribs 22 by which the web is penetrated and the slits are 55 formed without the displacement of any of the intervening parts from the plane of the web, the rolls being proportioned to provide suitable clearances at the bases of the ribs to accommodate the metal displaced on the 60 strand surfaces by the penetration of the ribs.

Such a manner of slitting the blank has the advantage of avoiding any incidental stretching of the portions by which the struts of the finished beam are provided and enables 65 the expansion of the blank without any intervening step. I have found, moreover, that the web slit in this manner may be given its ultimate flat expanded form by a single operation.

Thus the web may be completely 70 expanded in flat form, that is to say in lateral continuations of its plane, by a single continuous operation in which the flanges F without elongation are spread relatively to one another and the strands are uniformly 75 stretched by a direct pull in the plane of the web.

By complete expansion I refer to that degree of expansion which it is intended that the finished beam shall have and include expansion to any degree within a range which 80 conforms to the requirements of sound engineering practice.

For the purpose of the expanding operation it is preferred to employ an expansion guide 31 of the construction shown but other 85 means of continuously and progressively separating the flanges F until the expansion is completed may be employed. The expansion guide preferably consists of a lower member 32 and an upper member 33, these 90 being secured together along their marginal portions by suitable bolt fastenings 34. The adjoining faces of the members 32 and 33 are formed with recesses to provide a chamber or clearance 35 for the web of the blank. 95 The sides of the clearance are provided by ribs 37 which engage the chord portions of the blank. Beyond the ribs 37 the adjacent faces of the members 32 and 33 are recessed to provide clearances 38 for the flanges, the 100

- ribs 37 providing the inner sides of the clearances 38. The ribs 37 extend in divergent relation and at a suitably narrow angle from the front end of the expansion guide to points 5 more or less at the center of the length of said guide and beyond such approximately central points extend in parallel relation as shown in Figure 7. The clearances 38 conform in direction and length of extent to the ribs 37. 10 In their inclined portions the clearances 38 are of greater width than the thickness of the flanges F and gradually diminish in width toward the points where they commence to run parallel, at which points and for the rest 15 of their extent their width is still slightly greater than the thickness of the flanges F. The spreading thrust is exerted against the flanges F by the ribs 37 and the width of the clearances 38 is such that the outer faces of 20 the flanges F do not contact with the outer faces of the clearances, frictional resistance to the movement of the blank through the expansion guide being thereby minimized. The ribs 37 are suitably extended at their 25 front ends, as at 39, beyond the body portions of the members 32 and 33 to engage the chord portions of the blank before the web enters the expansion guide and the rib extensions 30 are provided with shoes 40 which engage the upper and lower edges of the flanges F before the latter enter the clearances 38. The supporting engagement of the rib extensions 39 and shoes 40 with the blank commences immediately in front of the center of the pass 35 of the slitting rolls 20 and 21 and insures the accurate introduction of the slitted blank into the guide 31.
- The ribs 37 act on the flanges F to thrust them relatively laterally outward during the 40 movement of the blank through the guide and as the flanges F are thus separated they continuously and progressively exert opposite and equal pulls on the slitted portion in directions of lateral outward continuation 45 of the plane of the web. The result of these pulling forces is that the strands are bent from their associated bonds in the plane of the web and extend diagonally in such plane, alternate strands extending in opposite di- 50 rections, and during their bending displacement are stretched in the directions of their length and of the plane of the web. It follows that the operation of expanding the web is at the same time an operation for 55 bringing it to its ultimate form in which the stretched strands and associated bonds lie flat in a common plane coincident with the original plane of the web and the expanded product has the same 60 length as the blank with which the operation started, the flanges and the continuous web parts attached thereto and which provide the chords of the completed beam being of the same length as in the original 65 blank. The expansion of the web is com-

pleted at the point at which the parallel extent of the flanges 37 and clearances 38 commences; and during the further travel of the blank in the expansion guide any inequalities or local irregularities in the flanges are smoothed or ironed out while the flanges are also definitely set in parallel relation. 70

The blank on its emergence from the expansion guide passes between upper and lower finishing rolls 41 and 42 by which 75 all irregularities on the surface of the expanded portion are reduced and the struts of the finished beam are set, the struts and the associated bonds lying flat in a common plane coincident with the plane with which 80 the operation started.

The slitting and finishing rolls are positively driven and are available, without further mechanism, for the feed of the blank through the apparatus. 85

By the rolls shown in Figure 3 the web is slitted in three longitudinal rows whereby the expanded beam is in the form of a simple lattice truss. It will be understood, however, that the web may be slit in two rows 90 or in more than three rows without varying the procedure or substantial results of the process. 95

Having fully described my invention, I claim:

1. The method of producing an expanded load bearing member from a heated flanged blank having a web between the flanges which consists in forming longitudinal rows of slits in the web by a scoring operation, the slits delimiting strands and bonds, and thereupon continuously and progressively separating the flanges without elongating them whereby to bend the strands and stretch them by a direct pull in the plane of the web until the slitted portion is completely expanded. 105

2. The method of producing an expanded load bearing member from a heated flanged blank having a web between the flanges which consists in forming longitudinal rows of slits in the web by a scoring operation, the slits delimiting strands and bonds, thereupon causing the flanges continuously and without elongation to follow diverging paths with resultant bending and direct pulling and consequent stretching of the strands in the plane of the web until expansion is completed, and thereupon causing the flanges to follow parallel paths in which they are set in parallel relation and maintain the previously completed expansion. 115

In testimony whereof I hereby affix my signature.

MAURICE D. BRODY.
